2,649,002

SEAMLESS TUBE DRAWING TOOL

Donovan P. Gremling, Shelby, Ohio

Application August 10, 1950, Serial No. 178,687

3 Claims. (Cl. 80—13)

1

This invention relates to machines for drawing seamless tubing by the axial rolling process wherein billets are forced by a ram over a point with a pair of pressure rollers traveling around the point for forming the billets into a seamless tube, and in particular this invention relates to an improved mounting for the points over which the billets are forced, wherein the point is journaled on a tubular spindle that telescopes over a mandrel with a ball thrust bearing behind the point to facilitate rotation thereof and with a cooling water opening extended into the point to hold the temperature of the point comparatively low.

The purpose of this invention is to reduce the friction resulting from rotation of comparatively long mounting sleeves on which points over which billets are forced are carried whereby the points rotate more freely and consequently wear longer.

In the conventional type of points over which billets are forced to form seamless tubing the points are provided on spindles and the length of the spindles increases the bearing surface area and at the extreme heat the rotation of the points is restricted. To obtain efficient operation it is desired that the point rotate as freely as possible and to accomplish this purpose this invention contemplates separating the points from the spindle and rotatably mounting the points on a tubular shaft with a ball thrust bearing behind the points so that the points only rotate and the rotating part is journaled against a ball thrust bearing to reduce the friction where the resulting force is applied.

The object of this invention is, therefore, to provide means for forming a point over which billets of seamless tube rolling mills are driven whereby the point, only, rotates and whereby means is provided for reducing the friction and temperature.

Another object of the invention is to provide a mounting for points of seamless tube mills wherein a cushion is provided for taking the shock load from the thrust bearing and associated parts.

A further object of the invention is to provide an improved mounting for the point of seamless tube mills over which billets are driven between pairs of rolls, which is of a comparatively simple and economical construction.

With these and other objects and advantages in view the invention embodies a conical shaped point rotatably mounted on a tubular shaft with the shaft extended from a sleeve telescoping on a spindle, with a ball thrust bearing between the point and shoulder of the sleeve and with a

2

spring between the end of the sleeve and a shoulder of the spindle.

Other features and advantages of the invention will appear from the following description taken in connection with the drawings wherein:

Figure 1 is a longitudinal section through a point of a seamless tube mill showing the point entering a billet being driven over the point and showing a pair of rolls that travel around the point to form the billet into a tube.

Figure 2 is a cross section through the point taken on line 2—2 of Figure 1.

Referring now to the drawings wherein like reference characters denote corresponding parts the improved seamless tubing forming point of this invention includes a conical shaped point 10, a shaft 11 on which the point is mounted, a sleeve 12 from which the shaft extends, a ball thrust bearing 13, a mandrel 14 and a spring 15 between the inner end of the sleeve and a shoulder 16 on the mandrel.

It will be understood that although the point 10 is illustrated with a substantially pointed outer end to provide a piercing point, the point may also be formed to provide a reeling point, and the slope of the point may be changed as may be desired.

In the design shown the point 10 is provided with a bore 17 in which the tubular shaft 11 is positioned and a bushing 18 may be provided at the end of the shaft. The bushing 18 may be replaced with a bushing of a different size as the point wears. The base of the point is provided with a counterbore 19 to provide clearance for a set screw 20 that is threaded into the shaft 11 to hold the ball thrust bearing 13 in position against a shoulder 21 and on a bearing surface 22 between the shaft 11 and sleeve 12.

The sleeve 12 is also provided with a bore 223 in which the end 23 of the mandrel 14 extends and, as illustrated in Figure 1 the mandrel is provided with an elongated slot 24 into which the inner end of a set screw 25, threaded in the sleeve 12 extends to key the sleeve to the spindle.

A space 26 is provided between the end of the spindle and inner end of the bore of the sleeve whereby the sleeve telescopes on the spindle providing a reciprocating action, thereby forming a cushion to relieve the thrust bearing 13 of the shock load.

The spindle is provided with an opening 27 through which cooling water passes to the bore 28 of the shaft 11 upon which the point 10 is carried.

With the parts formed in this manner a billet

29 driven against the point 10 is formed into a tube by the rolls 30 and 31 traveling around the point and tube and as wear develops in the point the bushing 18 may be removed and replaced, and as wear continues to develop the point may be replaced.

The ball thrust bearing facilitates spinning of the point and the spring 15 relieves the ball thrust bearing of the shock load resulting from driving force by which the billet is forced against the point.

It will be understood that modifications may be made in the design and arrangement of the parts without departing from the spirit of the invention.

What is claimed is:

1. In a seamless tube forming tool, the combination which comprises a mandrel having a reduced end portion and a bore therethrough, a shoulder on the outer surface of the mandrel spaced from the end of the reduced end portion and a longitudinally disposed slot extended inwardly from the outer surface of the reduced end portion, a sleeve having an extended tubular shaft at one end thereof slidably mounted on the reduced end portion of the mandrel, resilient means between the end of the sleeve and shoulder of the mandrel, a point for receiving a billet journaled on the tubular shaft of the sleeve, and a ball thrust bearing positioned between the base of the point and shoulder at the end of the sleeve, said sleeve having a set screw extended into the longitudinally disposed slot of the mandrel to limit the longitudinal movement of the sleeve on the reduced end portion.

2. In a seamless tube forming tool, the combination which comprises a mandrel having a reduced end portion and a bore therethrough, a shoulder on the outer surface of the mandrel spaced from the end of the reduced end portion and a longitudinally disposed slot extended inwardly from the outer surface of the reduced end portion, a sleeve having an extended tubular shaft at one end thereof slidably mounted on the reduced end portion of the mandrel, resilient means between the end of the sleeve and shoulder of the mandrel, a point for receiving a billet

4
journaled on the tubular shaft of the sleeve, a ball thrust bearing positioned between the base of the point and shoulder at the end of the sleeve, said sleeve having a set screw extended into the longitudinally disposed slot of the mandrel to limit the longitudinal movement of the sleeve on the reduced end portion, and a pushing in the point positioned against the end of the tubular shaft.

10 3. In a seamless tube forming tool, the combination which comprises a mandrel having a reduced end portion and a bore therethrough, a shoulder on the outer surface of the mandrel spaced from the end of the reduced end portion and a longitudinally disposed slot extended inwardly from the outer surface of the reduced end portion, a sleeve having an extended tubular shaft at one end thereof slidably mounted on the reduced end portion of the mandrel, resilient means between the end of the sleeve and shoulder of the mandrel, a point for receiving a billet journaled on the tubular shaft of the sleeve, a ball thrust bearing positioned between the base of the point and shoulder at the end of the sleeve, said sleeve having a set screw extended into the longitudinally disposed slot of the mandrel to limit the longitudinal movement of the sleeve on the reduced end portion, a bushing in the point positioned against the end of the tubular shaft, said point having a counterbore on the base and a set screw threaded in the tubular shaft for securing the ball thrust bearing in position on the sleeve.
